United States Patent

Des. 238,333

Patented Jan. 6, 1976

238,333

CONTAINER FOR LIQUIDS

Ronald Franklin Seddon, Skelmersdale, England, assignor
to Polythene Drums Limited

Filed Oct. 3, 1973, Ser. No. 403,194

Term of patent 14 years

Int. Cl. D9—03

U.S. Cl. D9—170

FIG.1

FIG.2

FIG.3

FIG.6

FIG. 1 is a front elevational view of a container for liquids, showing my new design;

FIG. 2 is a side elevational view;

FIG. 3 is a rear elevational view;

FIG. 4 is a top plan view;

FIG. 5 is a bottom plan view; and

FIG. 6 is a sectional view taken along line 6—6 of FIG. 1.

I claim:

The ornamental design for a container for liquids, as shown.
